DESIGN FOR A HORIZONTAL TANK STAND

Gilbert Holman Evans, Rockville Centre, N. Y.

Application June 19, 1934, Serial No. 52,241

Term of patent 14 years

To all whom it may concern:

Be it known that I, Gilbert Holman Evans, a citizen of the United States, residing in Rockville Centre, in the county of Nassau and State of New York, have invented a new, original, and ornamental Design for a Horizontal Tank Stand, of which the following is a specification, reference being had to the accompanying drawing, forming a part thereof, in which

Figure 1 is a perspective view of a horizontal tank stand showing my design; and

Fig. 2 is an end elevational view thereof.

The distinctive and dominant features of my design comprise substantially two spaced apart cradles presenting arcuate rest areas with longitudinally flat upper surfaces and vertical webs thereunder, these cradles being borne by the

tops of cylindrical rods arranged vertically in pairs with the rods of each pair relatively close together and the pairs of rods spaced apart, with flanged tie braces extending between and connecting the lower portions of each vertical pair of rods, and with a relatively small cylindrical tie rod extending horizontally between intermediate portions of said connecting tie braces, and a pair of similar horizontal tie rods of relatively small cross section at the top of the pairs of vertical rods connecting the end portions of said cradles.

I claim:

The ornamental design for a horizontal tank stand, as shown and described.

GILBERT HOLMAN EVANS.
